UNITED STATES PATENT OFFICE.

ROBERT A. TAYLOR, OF CINCINNATI, OHIO.

CARTON AND BLANK THEREFOR.

1,312,710.

Specification of Letters Patent. Patented Aug. 12, 1919.

Application filed April 26, 1919. Serial No. 293,009.

To all whom it may concern:

Be it known that I, ROBERT A. TAYLOR, a citizen of the United States, residing at Cincinnati, in the county of Hamilton and State of Ohio, have invented certain new and useful Improvements in Cartons and Blanks Therefor, of which the following is a specification.

My invention relates to improvements in carton and blank therefor. One of its objects is to provide an improved carton for display purposes, in which the container and lid are united so that when opened the lid section is guided into a position to serve 10 as an easel or support for the container, to hold the container in an inclined position best suited to display the contents thereof. Another object is to provide an improved blank preferably of one piece, from which 15 both the container member and the lid member may be produced by folding. Another object is to provide an improved blank and carton in which the walls are of double thickness and arranged to present only one 20 face of the sheet or stock to view, thereby providing for the use of stock which is faced and printed upon one side only. Another object is to provide an improved blank from which the container and lid may be 25 set up entirely by a folding operation, and without the use of paste, staple, or other similar fastening means. My invention also 30 comprises certain details of form, combination, and arrangement, all of which will be 35 fully set forth in the description of the accompanying drawings, in which:

Figure 1 is a plan of a blank suitable for producing my improved carton.

Fig. 2 is a perspective view of the container member and lid member set up and in position to be filled.

Fig. 3 is a perspective view of the two members approaching a closed position as compared with that shown in Fig. 2.

Fig. 4 is a central longitudinal section through a closed carton.

Fig. 5 is a view similar to Fig. 4 illustrating a modification.

Fig. 6 is a perspective view of the container and lid members in open position to display the goods to be carried therein.

The accompanying drawings illustrate the preferred embodiments of my invention in which 10 represents a blank cut from cardboard or paper stock and scored as indicated by dotted lines in Fig. 1, so as to be folded

to produce a box or container member 11 and a lid member 12, united by a connecting section 14, which is also a portion of the inner face or lining.

The blank, and carton when folded, is of such nature that it may be cut from stock which is faced or finished upon one side only, and requires to be printed upon one side only, and may be folded so as to produce a container member with double walls, and a lid member with double walls, and thereby presents only the single face, or finished face of the stock to view on the exterior and on the interior of said members, all of which are features of importance in the economic production and final appearance of the carton. The cartons are adapted to be shipped in the flat or blank condition and to be set up by a folding 65 operation without the use of glue, paste, or metal fastening devices, at the point where the cartons are to be filled.

In folding the blank to form the container and lid members 15 represents the 80 main outside section of the lid and 15' the lining therefor, while 16 represents the main or bottom section of the container and 16' the lining therefor. In folding the blank, it will be noted that the blank is unbroken 85 or continuous along its upper side, and is cut in from its lower side to partially separate that portion of the blank for the container from that portion of the blank forming the lid, so that either the lid or the container may be folded first, and the folding of either one up to the point where the continuous upper portion of the blank is to be folded into place may be carried out without inconvenience due to their being 90 connected together, and said continuous upper portion of the blank is folded into both members at a single operation.

If the lid is to be folded first, its end sections 17 and 18 are first lifted at right angles 100 to section 15, and sections 18 are turned inwardly at right angles to sections 17. The sections 19, 20, and 21 are then lifted at right angles to section 15, folding along the scored line 22. Then a fold is made along 105 the line 24, and another along the line 25, whereby the section 20 is brought face to face with section 19, with the sections 18 locked between them at their ends, and the section 21 is brought against the inner face of section 15 and one edge thereof placed beneath the curved tongue 26 to hold these sections 110 17,

18, 19, 20, and 21 in their adjusted position while similar folds are being made using the sections 17', 18', 19', 20', and 21' of the container portion of the blank, the edge of section 21' being locked beneath the curved tongue 26'.

A fold is then made along the scored lines 27 and 27', and then along the lines 28 and 28' which causes the sections 29 and 30 of the lid and sections 29' and 30' of the container to fold face to face locking between them the sections 18 of the lid and sections 18' of the container, and bringing the sections 14, 15', and 16' into position to form a lining for the lid and container members, and completing the carton substantially as illustrated in Fig. 2, ready to receive the goods to be packed in the container member thereof. The sections 32 and 32' serve as lining sections for the ends of the container, and the sections 33, 33', and 34' serve as lining sections for the lid member. The section 31 may be omitted if desired, and when employed is designed to carry and display advertising matter when the carton is on display, and when it is closed the section 31 folds as an additional protection over the top of the goods and within the lid as indicated in Fig. 4.

In the position Fig. 2 the sections 33 and 33' serve as a portion of the lining of the lid. When the lid is closed over the container as illustrated in Fig. 4 the sections 33 and 33' fold along the scored line 36 one upon the other, and said sections rest between the end of the container and the end of the lid. The section 32 folds relative to section 16' along the line 35, the section 33 folds relative to section 32 along the line 37 and the section 33' folds relative to section 14 along the line 38. The sections 33 and 33' serve to take up slack material when the lid is fitted over the container, and need not necessarily be located at the position illustrated in Figs. 1, 2, and 4, but may be located anywhere between the scored line 34 and the scored line 37. As illustrated in Fig. 5 the sections 40 and 41 corresponding to the sections 33 and 33' of Figs. 1 and 4 are located close to the scored line 34, and fold one upon the other within the lid. The tongues 26 and 26' are formed by cutting curved slits in the blank sections 15 and 16, and said locking tongues facilitate a rapid setting up of the cartons from the blank form. A slit 45 separates the section 14 from the section 30, and thereby provides for the movement of the section 14 relative to the lid member as indicated in Fig. 3, during the operation of placing the lid on the container or removing it therefrom. The blank can be made in two parts united

by a paste lap say near the line 37 in place of a one piece blank.

The article herein illustrated and described is capable of considerable modification without departing from the principle of my invention.

What I claim is:

1. A one piece carton blank comprising a section to be folded into a lid and a section to be folded into a container, said blank being scored at the union of said sections to guide said sections to a telescopic closed position and to a partially telescopic display position in which one end of the container rests upon the edge of one end of the lid. 75

2. A one piece carton blank comprising a section to be folded into a lid, a section to be folded into a container and a connecting section forming a lining for the lid and folded upon itself to take up the slack when in closed position and limiting the relative movement of the sections in display position to a partially telescopic position of the container section into the lid section with one end of the container section resting upon the edge of one end of the lid section. 85

3. A one piece carton blank continuous 90 across one side and divided from the opposite side into a lid forming section and a container forming section.

4. A carton blank continuous across one side and the opposite side divided into a 95 lid forming section and a container forming section, said blank being adapted to form when folded double walled lid and container members united through their inner wall.

5. A carton blank divided at one side into 100 a lid forming section and a container forming section, said blank when folded forming double walled lid and container members united through their inner wall.

6. A one piece carton blank continuous 105 across one side and the opposite side divided into a container member and a lid member having an integral connecting member limiting the movement of said lid member relative to said container member. 110

7. A one piece carton comprising a double walled lid member and a double walled container member set up entirely by a folding operation, the blank for said carton being scored at the union of said container and lid to guide said container and lid to a telescopic closed position and to a partially telescopic display position in which one end of the container rests upon the edge of one end of the lid. 115

In testimony whereof I have affixed my signature.

ROBERT A. TAYLOR.
